UNITED STATES PATENT OFFICE.

SIMEON S. JACKSON, OF BOSTON, MASSACHUSETTS, ASSIGNOR TO THE STAFFORD COMPANY, OF READVILLE, MASSACHUSETTS, A CORPORATION OF NEW JERSEY.

WEFT-PARTER FOR LOOMS.

1,131,841.

Specification of Letters Patent. Patented Mar. 16, 1915.

Application filed August 23, 1912. Serial No. 716,703.

To all whom it may concern:

Be it known that I, SIMEON S. JACKSON, a subject of Great Britain, residing at Readville, Boston, in the county of Suffolk, State 5 of Massachusetts, have invented a certain new and useful Improvement in Weft-Parters for Looms, of which the following is a specification, reference being had therein to the accompanying drawings.

10 One portion of the invention provides for locating the fixed and movable weft-parting members at the inner side of the temple-bar, between the latter and the adjacent end of the cap for the temple roll, so as to enable the weft-end to be parted at a point 15 very close to the selvage of the fabric being woven. The fixed parter-member is clamped between the inner side of the bar and a vertical plate formed upon the inner end of the 20 said cap, which may conveniently be effected by means of a transverse bolt serving to fasten the cap to the bar.

A feature of the invention consists in the employment of the said plate and the 25 adjacent portion of the temple-bar or shank as guides for the lever constituting a carrier for the movable parting blade or blades.

Another feature of the invention consists in supporting the said lever by means of a 30 rounded projection thereon working in an open concave seat or half-bearing. The lever rocks or swings upon the said seat, an ordinary pivot being dispensed with. The lever and the weft-parting means carried 35 thereby are returned to their normal position by a spring that acts with a tendency to hold the lever to the said seat, and that also holds the lever from movement lengthwise. A removable fixed stop upon the bar 40 or shank acts to prevent the lever from leaving the seat. The removal of this fixed stop permits the lever to be readily removed and replaced.

In conformity with another feature of the 45 invention, the movable parting member is constructed so that in the parting movement thereof it parts or cuts the weft-end contained within the notch or open eye which is provided for the reception of the 50 weft-end to be parted, and in the return movement it closes the said eye against the entry of the running weft. This result is secured by means of a gate with which the said parting member is provided.

The invention includes, also, various other 55 improvements in construction.

An embodiment of the invention is illustrated in the drawings, in which:

Figure 1 is a side elevation of a loom temple and weft-parter embodying the invention. Fig. 2 is a top or plan view thereof. Fig. 3 is an elevation of the rear portions of the temple, viewed from the outer side. Fig. 4 is a rear elevation of the temple and weft-parter. Fig. 5 is a view in 65 vertical section in a vertical plane immediately alongside the lever.

Having reference to the drawings, a temple-stand is represented at 1, the temple-bar at 2, and 3 is the expanding spiral 70 spring which encircles the rounded part of the said temple-bar. The said spring is confined as usual between the guide 4 at the front end of the temple-stand and the shoulder 5 of the temple-bar. It acts in 75 well-known manner to hold the temple-bar and the temple-head in their normal rearward position, and to return them to such position after they have been moved forward through the contact of the advancing 80 lay with the temple heel 7 projecting downward from the bar or shank 2, of which it is a part. The too'ed temple roll, or bur roll, is marked 8 in Figs. 1 and 4.

The trough or pod for the bur roll is 85 marked 9. In this instance it is, for convenience, integral with the bar or shank 2. The cap for the said roll is marked 10. It is a separate piece. It is formed at its outer end, *i. e.*, that adjacent the bar or shank 2, 90 with a downwardly extending plate 101, which is prolonged forward as shown in Figs. 1 and 2. The cap is secured to the bar or shank 2 by means of a screw 11 extending transversely through a hole in the 95 bar or shank and screwing into a threaded hole that is tapped in the plate 101. The squared enlarged head of the said screw is located at the outer side of the bar or shank. The roll 8 is mounted upon the stem of a 100 long screw-pin 12, which occupies holes in the down-turned inner end of the cap, in the plate 10, and in the bar or shank. This screw-pin prevents the cap, and the fixed parting member presently to be described, 105 from swinging around the pin 11.

At 13 is the notch, slit, or open eye that is formed in the rear end of bar or shank

2, in line horizontally with the narrow horizontal opening between the rear edges of the cap and pod or trough, to permit the weft-end that is to be parted to pass forward into position to be engaged by the movable parting member or members.

The fixed parting member 14 comprises a plate that intervenes between the plate 101 of the cap and the inner side of the bar or shank 2. The screw 11 and screw-pin 12 pass through holes in the said member, and it is held in place by being clamped tightly between said plate 101 and the bar or shank. The acting portion of member 14 projects rearward above the notch, slit or open eye 13, as shown best in Fig. 5.

At 15, 15, are two movable parting members, one thereof at either side of fixed member 14. The carrier-lever 16 for the said members 15, 15, is fitted between the bar or shank 2 and the forward portion of plate 101. The lever is confined in position between the inner surfaces of the bar or shank and the plate, which constitute lateral guides therefor. The parting members 15, 15, are attached to the upper arm of the carrier-lever and extend rearward and downward therefrom. They are formed at their free extremities with upwardly and rearwardly facing hooks 151, to coact with the under edge of the fixed member 14 in parting the weft-end. To insure proper cutting or parting of the weft-end as the hooks pass the acting edge of member 14 in the working stroke of the members 15, 15, the latter are formed of elastic material, and are bent or set so as to bear with moderate pressure against the opposite surfaces of fixed member 14, so that in their movements they slide upon such surfaces. To accommodate the carrier-lever 16 and the members 15, 15, the adjacent sides of plate 101 and arm or shank 2 are cut away at front and rear of the screw 11, as shown in Fig. 2, to provide spaces in which such parts are received and in which they work.

As in my prior Letters Patent No. 981,859, dated Jan. 17, 1911, the movable parting members are shown herein arranged to be moved by the advancing stroke of the lay into position to receive the weft-end between their acting portions and that of the fixed member 14, and to be moved by a spring as the lay makes its rearward stroke, to part the weft-end through coaction with the said fixed member.

For the actuation of the lever 16 by the lay, the said lever is furnished with a heel 17. The lay in advancing encounters the said heel 17, and thereby rocks the said lever to depress the hooks 151 of the parting members 15, 15, below the acting edge of fixed member 14, before the lay engages the temple-heel 7 to drive the temple forward.

65 In the present instance the spring 18 by

which the working movement of the parting members is produced is formed at 181 into a coil which fits upon a supporting stud 19 that projects from the outer side of the bar or shank 2. An upwardly-projecting arm 182 of the said spring rests against one side of the projecting head of the screw 11, the said head constituting an abutment from which the spring reacts. To prevent the said arm 182 from slipping off the said head, the latter is circumferentially grooved at 111, Figs. 2 and 4, to receive the arm. The other arm of the spring extends forwardly and downwardly and is formed into a coil which is fitted upon a round stud 20 projecting outward from the lever 16. The spring acts to hold the stud 20 normally against the forward side of heel 7 of the temple, with parting-members 15, 15, in an elevated position as in Figs. 1, 3, 5.

For the pivotal mounting of the lever, it is formed with a rounded projection 161, Fig. 5, and an open concave seat or half-bearing 21 is provided in a lateral projection formed on the inner side of the bar or shank 2. The said projection fits said seat, and works therein as the lever is rocked. The seat being an open seat, the lever may be applied thereto by simply introducing the lever edgewise between plate 101 and bar or shank 2, and causing the projection to enter the seat. After the lever has been seated, the coil of the forwardly extending arm of the spring 18 is to be engaged with stud 20. The action of the spring will tend to cause projection 161 to remain in the seat. To prevent the lever from being thrown out of the seat, the fixed stop 22 is provided. Such stop is constituted by the inwardly-projecting head of a screw set in the bar or shank 2. Its position is at the front of the forward edge of the lever, so that when the lever and parting members 15, 15, are thrown by the spring 18 into their normal position shown in the drawings the said edge will make contact with the said stop, which will limit the opening movement of the parting members. When the edge is in contact with the stop the continued pressure of the spring will tend to bear the rounded projection of the lever against the bottom of the open seat. By simply removing the screw-stop 22 and uncoupling the spring from stud 20 the lever 16 will be freed, and may be lifted out of place. It may subsequently be returned to place readily, and after the screw-stop 22 has been restored to its place the parts will be in condition for further use.

The portion of the spring 18 between the two coils thereof acts as a radius-arm in holding the lever 16 from movement lengthwise.

In the normal position of the parting-device with the hooks 151 elevated above the

notch or open eye 13, the said hooks are shielded between the outer end of the cap 10 and the rear end of arm or shank 2, and by the rear end of the parting member 14, 5 in such manner that the running filling cannot catch and loop upon the hooks.

In the advance of the lay the contact of some portion of the latter with the heel 17 rocks the lever 16 so as to carry the movable 10 parting-members or blades 15, 15, downward until the hooks of such members or blades pass below the notch or open eye 13. During the intermediate portion of the descent or rise of the movable parting-members 15 or blades the weft-end which requires to be parted or cut enters the said notch or open eye. As the lay recedes, relieving the heel of the lever 16 of pressure, the spring 18 operates the lever to swing it in the reverse direction, raising the movable parting-members or blades, so that their hooks carry the weft-end against the under edge of the fixed parting member 14 and part the weft-end.

25 To prevent the running weft from being thrown into the notch or open eye 13 as the lay beats up and passes the front center, at which time the hooks are depressed, so as to be caught and parted by the hooks in 30 their upward movement, I provide one or each of the movable parting-members or blades 15, 15, with a horn 152 opposing the hook 151, there being an opening 153, Fig. 5, between the points of the hook and horn 35 to admit a weft-end into position above the hooks at the proper time. The movement of the movable parting-members or blades produced by the lay in beating-up carries the horn down across the notch or open eye 13 40 to act as a gate bridging the same. In such position of the gate it prevents the running filling from entering into the notch or open eye so as to be caught by the hooks as the latter rise during the receding movement of 45 the lay. The horn or gate has an inclined or beveled inner edge. In the descent of the parting-members or blades 15, 15, such edge acts upon a filling-end that has entered the notch or open eye to draw such filling-end forward within the notch or open eye 50 into the path which subsequently is taken by the hook-shaped parting or cutting portions of the movable blades in their rising movement.

55 I claim as my invention:—

1. In a weft-parter for looms, in combination, a loom-temple, a parting-member thereon, a lever pivoted upon said temple, having one or more coöperating parting 60 members attached to its upper arm, extending rearward and downward therefrom, and furnished with rearwardly and upwardly facing hooks, said lever provided with a depending heel to receive the stroke of the 65 advancing lay of a loom and also having a

lateral stop-projection to engage with the temple, said stroke operating the lever to open the parting-members to receive the said thread, and a spring operating to return the said stop-projection against the 70 temple and move the hooks upward to part the thread against the opposing parting member.

2. A weft-parter for looms provided with coöperating parting-members, one of which 75 in the parting movement parts the thread against the other and in the reverse movement closes the entrance between such parting-members, and operating means.

3. A weft-parter for looms provided with 80 coöperating parting-members, one thereof having a thread-engaging hook which in the parting movement parts the thread against the other member, and also having a gate which in the reverse movement closes the 85 entrance between the parting members, and operating means.

4. A weft-parter for looms provided with coöperating parting-members, one thereof having a thread-engaging portion which in 90 the parting movement parts the thread against the other member, and also having a gate facing said thread-engaging portion which in the reverse movement closes the entrance between the members and also acts 95 upon a thread therein to draw the same into the path to be taken by the said thread-engaging portion in the next parting movement, and operating means.

5. In a weft-parter for looms, in combination, a loom-temple, coöperating parting-members, one thereof having a thread-engaging hook which in the parting movement parts the thread against the other member, and also having a gate opposite said hook, 100 which in the reverse movement closes the entrance between the members, said hooked member adapted to be engaged by the advancing lay of a loom to occasion said reverse movement, and a spring acting in the 105 retreat of the lay to occasion the parting movement.

6. In combination, a temple-bar or shank, a temple-roll, a removable cap therefor, a weft-parting member between the outer end 115 of said cap and the inner side of said bar or shank, means securing the cap to the bar or shank with the said member between them and clamping such member fixedly in place, and a coöperating movable parting member. 120

7. In combination, a temple-bar or shank, a temple-roll, a removable cap therefor having a vertical plate at its outer end, a weft-parting member having its shank-portion between said plate and the inner side of the 125 bar or shank, a transverse screw securing said plate, member, and bar or shank together, and a coöperating movable parting member.

8. In combination, a temple-bar or shank, 130

- a temple-roll, a removable cap therefor having a vertical plate at its outer end, a weft-parting-member having its shank between said plate and the inner side of the bar or shank, a transverse screw securing said plate, member, and bar or shank together, a pin on which said temple-roll is mounted, occupying holes in the plate, the said weft-parting member, and the said bar or shank, 10 and a coöperating movable parting member.
9. In combination, a loom-temple provided with an open concave seat or half-bearing, a lever-member provided with weft-parting means and with a rounded pivotal portion which occupies said open seat or half-bearing, and a spring operating said lever-member and also holding its rounded pivotal portion in such open seat or half-bearing.
10. In combination, a loom-temple provided with an open concave seat or half-bearing, a lever-member provided with weft-parting means and with a rounded pivotal portion which occupies said open seat or half-bearing, and a spring operating said lever-member, holding its rounded pivotal portion in such open seat or half-bearing, and restraining the lever member from longitudinal movement.
11. In combination, a loom-temple provided with an open concave seat or half-bearing, a lever-member provided with weft-parting means and with a rounded pivotal portion which occupies said open seat, a spring operating such lever-member and also holding its rounded pivotal portion in such open seat, and a removable stop determining the extent of the movement of the lever-member and preventing it from leaving the open seat.
12. In combination, a loom temple having a bar or shank, a temple-roll, and a temple-roll cap provided with a plate at the outer end thereof, said temple also provided with an open seat or half-bearing, a lever-member furnished with weft-parting means and with a rounded pivotal portion which occupies said open seat or half-bearing, said lever-member working between the said plate and the bar or shank of the temple,
13. In combination, a loom-temple having a bar or shank and a temple-roll cap provided with a vertical plate at the outer end thereof, one of said parts furnished with an open seat or half-bearing, a lever-member provided with weft-parting means and with a rounded pivotal portion that occupies said open seat or half-bearing, with said lever-member confined between and guided by the said plate and the said bar or shank.
14. In combination, a temple-bar or shank, a removable temple-roll cap provided with a vertical plate at the outer end thereof, one of said parts furnished with an open seat or half-bearing, a weft-parting member between said plate and the bar or shank, means securing the cap to the bar or shank with the said member clamped between them, and a lever-member provided with weft-parting means and with a pivotal portion that occupies said open seat or half-bearing, with said lever-member guided laterally by the plate and bar or shank.
15. In combination, a temple-bar or shank, a removable temple-roll cap provided with a vertical plate at the outer end thereof, one of said parts furnished with an open seat or half-bearing, a weft-parting member between said plate and the bar or shank, means securing the cap to the bar or shank with the said member clamped between them, a lever-member, operated in one direction by the lay, provided with weft-parting means and with a pivotal portion that occupies said open seat or half-bearing, with said lever-member guided laterally by the plate and bar or shank, and a spring holding the pivotal portion of the lever-member in the open seat or half-bearing and operating said lever-member in the other direction.

In testimony whereof I affix my signature in presence of two witnesses.

SIMEON S. JACKSON.
